METHOD OF CASTING BALL INTEGRAL WITH THE INK FEED SECTION OF A BALL POINT PEN

Louis H. Morin, Bronx, and Otto Gries, New Rochelle, N. Y., said Otto Gries, assignor to Coats & Clark Inc., New York, N. Y., a corporation of Delaware

Application October 5, 1956, Serial No. 614,157

4 Claims. (Cl. 29—527)

This invention relates to ball point pens and particularly to the method of producing the ink feed section of a ball point pen, whereby, production of sections of this type and kind is materially simplified and, further, whereby a positive and definite control is provided in adapting the section to each ball cast therein and, still further, to the control of ink feed to adapt the section to inks of different characteristics.

The novel features of the invention will be best understood from the following description, when taken together with the accompanying drawing, in which certain embodiments of the invention are disclosed and, in which, the separate parts are designated by suitable reference characters in each of the views and, in which:

Fig. 1 is an enlarged sectional view of a section made according to my invention, indicating part of the cartridge to which the section is attached in dot-dash lines.

Fig. 2 is a sectional view through a pair of dies, showing an ink feed section cast with an integral ball within the end of the section and indicating, diagrammatically, part of the ball delivery mechanism.

Fig. 3 is a view, similar to Fig. 2, showing the upper die in raised position, preparatory to freeing the casting from the dies for movement to a trimming station.

Fig. 4 is a view, similar to Fig. 3, showing both of the dies freed from the cast or moulded product, with the latter still in the casting position.

Fig. 5 is a view, similar to Fig. 4, diagrammatically illustrating the trimming of the product at a trimming station to one side of the dies and also illustrating diagrammatically a forming operation performed at said station.

Fig. 6 is a view, similar to Fig. 2, diagrammatically illustrating the delivery of a ball to the cavity of the dies, preparatory to injection of the casting material into the dies, as illustrated in Fig. 2; and

Fig. 7 is a face view of a modified form of die construction which can be employed.

Our invention deals with the method of casting integrally with the ink feed section, sometimes referred to as a nipple or nib, with an integral writing element such, for example, as a ball in producing what is generally referred to as a ball point pen.

In Fig. 1 of the drawing, we have shown the product according to our invention, namely the ink feed section 10, which comprises a large diameter portion 11, a smaller diameter lower portion 12, the portions 11 and 12 having registering bores 13 and 14, respectively, the bore 14 being slightly smaller in diameter than the bore 13, the latter bore 14 having an ink feed discharge passage 15 having direct contact with a writing element in the form of a ball 16 held in position by a contracted end 17. The seat 18 for the ball is fashioned by a forming operation, later described, to control flow of ink to the surface of the ball to provide the required feed with inks having different characteristics or viscosities.

In Fig. 1 of the drawing, we have indicated at 19, in dot-dash lines, part of the ink cartridge which is assem-

2

bled upon the enlarged tubular end portion 11 of the section 10. It will be noted that the upper end of the large diameter portion 11 is bevelled, as seen at 20, which facilitates assemblage of the section with the cartridge 19.

Turning now to Figs. 2 to 6, inclusive, in these figures 21 and 22 diagrammatically illustrate a pair of dies which, for purposes of description, can be identified as upper and lower dies, respectively. These dies collectively form, by registering impression cavities 23 and 24, the cavity of the dies forming the resulting end product, namely the ink feed section 10 which is shown in section. The cavities 23 and 24 join on the parting line 25 of the dies, which parting line forms the shoulder 26 between the end portions 11 and 12 of the section 10. It will be noted, in this connection, that the sprue or inlet gate 27 is formed, for the most part, in the die 21, so that the contracted end of the passage, as at 28, is positioned only above the parting line 25. This results in leaving a clean lower surface to the shoulder 26 in the trimming operation, as will appear from a consideration of Fig. 5 of the drawing.

At 29 is diagrammatically shown the injection nozzle, through which suitable moulding or casting material is pressure injected into the die cavity from a suitable source of supply and, while different materials might be used, it is preferred that a tin alloy be used in order to resist the action of many types and kinds of inks.

Turning now to the opposed side of the die, here the dies are recessed on adjacent surfaces to receive a transfer core pin 30 which extends into an enlarged portion 31 in the dies, which forms a collar or transfer hub 32 on the end of the pin and, here again, a contracted portion 33 is disposed only in the die 21, similar to the contracted portion 28, to result in the clean trimming, as referred to above.

From the foregoing, it will be apparent that, in pressure injecting the moulding or casting material into the die cavity, the cast collar portion 32 is simultaneously formed on the pin 30 so that, when the dies are separated, as noted in Fig. 4, the casting can be moved to a trimming and forming station at one side of the dies, as noted in Fig. 5, at which station a forming operation, later described, is performed and the casting is trimmed.

The lower end of the cavity 24 of the die 22 has a contracted portion 34 forming the contracted end 17, noted in Fig. 1 of the drawing, and this contracted portion terminates in a shoulder 35 bordering a concaved ball receiving recess 36, into which a ball 16 is dropped by the medium of a delivery member, diagrammatically shown at 37. The ball delivery is illustrated in Fig. 6 of the drawing, in which figure the member 37 is disposed directly above the die cavity, including the bore 38 opening into the upper end of said cavity. It will be noted that the upper end of the bore 38 has a conical or flared portion 39, which facilitates movement of a core pin 40 into the cavity, as well as the dropping of the ball 16 into the cavity from the member 37.

The member 37 is movable into delivery and non-delivery positions, as noted in the several views and, while at the delivery position, a discharge latch 41 is intermittently rotated to free one of the balls 16 by withdrawal of the end 42 of the latch; whereas, the end 43 engages the next adjacent ball; whereupon, in return of the latch 41 to operative position, said next adjacent ball will be positioned at the delivery end 42, as will be apparent.

The core pin 40 has an enlarged upper end 44, which forms the large diameter bore 13 in the resulting casting and a smaller diameter end 45, which forms the bore 14. At the terminal end of the reduced end 45 is a reduced projection 46, shown in section in Fig. 2, and this projection has a rounded lower end 47 to set upon the ball

16, thus positively positioning and holding the ball upon its seat 36 in the lower end 22. The reduced end 46 forms the reduced feed passage 15 on the section or nib 10, as will be apparent.

Turning now to Fig. 5 of the drawing, in this figure, we have diagrammatically shown at 48 a forming tool or plunger, which will have a regulated and controlled movement upon the ball 16 when the cast product is positioned at the trimming station and supported by the transfer pin 30. It is also preferred that suitable back-up means, not shown, will be provided to resist the action of the forming member 48, it being understood that no great degree of force is necessary to perform the desired forming operation, bearing in mind that the metal is still in a warm state while positioned at said station. Action of the member 48 upon the ball 16 cast in the section 10 is to provide the predetermined clearance at the upper spherical surface of the ball to control and regulate the flow of ink to the ball for delivery to the lower surface of the ball in performing the writing operation. This operation also frees the ball to the required degree for proper operation for smooth easy writing with any desired ink. It is pointed out, at this time, that no attempt is made to show the clearance in the accompanying drawing for the reason that the clearance is slight.

Turning now to Fig. 7 of the drawing, we have here indicated diagrammatically, in part, two dies 49 and 50 which have a vertical parting line 51, instead of the horizontal parting line 25 noted in Fig. 2 of the drawing. This is simply illustrated to show that, in some instances, it might be desirable to form the resulting cast product with this type of die structure, the only difficulty being that slight markings might prevail on the outer peripheral surfaces of the upper and lower tubular portions 11 and 12 of the resulting product and this is obviated by maintaining the parting line in alignment with the shoulder 26, as noted in the other figures. With the structure of Fig. 7, it will be apparent that the admission sprue or gate passage 27 will be at a higher point on the dies, as noted at 27' in Fig. 7, and this will also be true of the location of the transfer pin, indicated in dotted lines at 30' in Fig. 7, otherwise, the structure of the dies 49 and 50 will be the same as the dies shown in Figs. 1 to 6, inclusive, and, for this reason, no further detailed description is deemed to be necessary.

The method will be readily understood from a consideration of Figs. 2 to 6, inclusive, the first step being to deliver a ball 16 to rest upon the seat 36 in the lower die 22, as noted in Fig. 6 of the drawing, in the manner previously described; whereupon, the member 37 is moved out of alignment with the aperture 38 and the core pin 40 is then moved down into the die cavities into engagement with the ball 16, as noted in Fig. 2 of the drawing; whereupon, the nozzle 29 will be held in pressure engagement with the closed dies and the moulding or casting material injected into the cavities to form the complete casting, as clearly noted in Fig. 2, after which, the core 40 is then moved into the raised position, shown in Fig. 3, and the upper die 21 also raised, leaving the casting momentarily supported on the lower die 22 and the core pin 30 with the nozzle 29 moved away from the dies; whereupon, the lower die 22 is moved into the position shown in Fig. 4; thus leaving the casting supported upon the pin 30 and free for movement to the casting and forming station, which is to the left of the dies, as noted in Fig. 5 of the drawing. Then the forming tool 48 is moved upwardly against the backed cast product for the purposes previously stated and, then, the product is trimmed to remove the gate or sprue part 27' and the sleeve part 32, the latter being stripped from the pin 30 and the result of this trimming operation is diagrammatically illustrated in Fig. 5. The trimmed parts 27', 32 are dropped into a suitable receptacle, not shown, whereas, the finished trimmed product, namely the ink

feed section or nib 10, is dropped into another receptacle, suitable means, not shown, being provided at the trimming and forming station to control these separate delivery or collection of the parts.

It will be understood that the curved recess 36 projects beyond the end of the cavity proper by virtue of the seating of the ball in this recess and, from this standpoint, it can be said that the recess projects beyond the cavity of the die.

The element 16 may be generally referred to as a marking or writing element in the sense that any type and kind of a flowable material contained in the feed section can be transmitted or transferred in rotation of the element to dispose the material on an outer surface of the element to be applied to any surface engaged by the element. From this standpoint, it will be apparent that devices of the type and kind under consideration can be used in conjunction with various types and kinds of materials that are subject to usage as described and the illustration and descriptive use herein given is only by way of illustrating one adaptation and use of the invention. In the several other uses that may be had, the shape, contour and size of the section will, of course, vary, the dies being made to suit the different shapes and forms which are desired. However, in all instances, the marking element will be, in part, exposed at one end of the section and also exposed to the interior or bore of the tubular section.

Further, in connection with varied uses, it will be understood that the section can be moulded from any type and kind of metal or metal alloy or from various types and kinds of plastics, the latter being true as and when the material employed will have no detrimental effect upon the particular plastics or metal used.

It will be noted in Figs. 2, 3 and 6 of the drawing that a small recess or aperture 36' extends from the base of the seat 36 and the purpose of this aperture is to cause the casting material to extend thereto, in the event that a ball should not be positioned in the die cavity, as illustrated in Fig. 6 of the drawing, and, thereafter, a cast section or nib formed. The resulting protruding portion of the casting formed by the recess 36' would clearly indicate, by what might be termed a flag, to the operator that a ball had not been positioned in the casting and, thus, the casting can be rejected or handled as other scrap or trimmings of the machine would be handled. It will be understood in this connection that, if the recess 36' were not employed, a rounded cast end would appear on the resulting product which might simulate the presence of a ball.

With my improved method, it will be apparent that any variations which may prevail in the size of the preformed ball or other marking element will be automatically compensated for by reason of the moulding or casting of the tubular section or nib upon the element which is deposited in the die cavity. By virtue of this fact, a more positive and definite control of flow of the material contained in the section or nib is provided in any particular run of successive castings produced from elements which are presumably to be of a common size.

Having duly described our invention, what we claim as new and desire to secure by Letters Patent is:

1. The herein described method of producing a tubular device having a ball positioned at and protruding beyond one end of said device, which comprises positioning a ball at one end portion of the cavity of a pair of relatively movable dies with said ball seating in a recess extending beyond the limits of said cavity, supporting the ball in the cavity by a core pin positioned centrally of the cavity and defining the bore of a tubular section to be formed in said cavity, pressure injecting heated moulding material into the die cavity around said pin and that part of said ball exposed to the cavity, forming by said core pin, a passage placing the bore of the section in direct communication with that part of the ball exposed to said passage for the transfer of a flowable material contained

in the bore of the section to the surface of the ball exposed at the end of the section in rotation of the ball in said section, and shaping that part of the section in which the ball is arranged to provide free rotation of the ball and passage of the flowable material over the surface of said ball.

2. The method as defined in claim 1, wherein the recess seat for the ball includes an extended aperture exposed to the die cavity, whereby, in the event that a ball is not deposited in said recess and a pressure injection of moulding material is introduced into the die cavity, a protruding cast flag will be formed on the resulting casting extending beyond the normal limits of a ball to indicate formation of an improper casting.

3. Method of forming a nib of a ball pen with a ball therein which comprises arranging a ball at and projecting beyond one end of a mold cavity of a pair of relatively movable dies, arranging a core pin in said cavity and positioning the pin to engage said ball within said cavity, arranging a transfer means in the dies, pressure-injecting heated molding material through a gate passage into the die cavity around said core pin, transfer means and that part of said ball exposed in the cavity, withdrawing said core pin, separating the dies to free the molded product, moving said product with the aid of said transfer means from the dies to a trimming and forming station, actuating said ball at the forming station to provide a predetermined clearance of the ball in said section and trimming the product in forming the resulting end product.

4. Method of forming a nib of a ball pen with a ball therein which comprises arranging a ball at and projecting beyond one end of a mold cavity of a pair of relatively movable dies, arranging a core pin in said cavity and positioning the pin to engage said ball within said cavity, arranging a transfer means within and between the dies, pressure-injecting heated molding material through a gate passage into the die cavity around said core pin, transfer means and that part of said ball exposed in the cavity, withdrawing said core pin, separating the dies to free the molded product, moving said product with the aid of said transfer means from the dies to a trimming and forming station where said trimming operation is performed, and actuating said ball, at said station, by controlled pressure to control clearance and feed of a flowable material through the section to the marking surface of said ball.
